UNITED STATES PATENT OFFICE.

ARTHUR F. DERSE, OF UNION COURSE, AND WILLIAM B. WILSHUSEN, OF MOUNT VERNON, NEW YORK.

HINGE FOR FOLDING CHAIRS.

Application filed August 5, 1921, Serial No. 489,981. Renewed February 28, 1925.

To all whom it may concern:

Be it known that we, ARTHUR F. DERSE, a citizen of the United States, and a resident of Union Course, in the county of Queens 5 and State of New York, and WILLIAM B. WILSHUSEN, a citizen of the United States, and a resident of Mount Vernon, in the county of Westchester and State of New York, have invented a new and useful Hinge 10 for Folding Chairs, of which the following is a specification.

This invention relates to folding chairs of the character disclosed in application Serial No. 410,840 filed September 17, 1920.

15 In that application a two-part seat of relatively rigid material is pivoted to pivotally connected legs and the centre pivot connecting the two parts of the seat together consists of a wire bent into three 20 lengths, one, a long length, and the other, two short lengths that are coaxial with each other and parallel to the long length. When subjected to stresses the wire is apt to become distorted.

25 The main object and feature of this invention is to provide a hinge for the central part of the seat that will adequately resist stresses to which it may be subjected.

In the accompanying drawings the invention is embodied in one preferred and concrete form in which—

Figure 1 is a perspective view of a chair embodying the invention.

Figure 2 is a bottom plan view of the two- 25 part seat showing the central hinge.

Figure 3 is a sectional view on the line 3—3 of Figure 2.

1 indicates the legs pivotally connected together in the manner described in the application referred to and also pivotally connected, at 2, to the two-part seat 3 and 4. 40 5 indicates the central hinge connecting the two parts of the seat and consists, as shown, of a wire bent into two sets of parallel lengths, the sets being arranged end to end. 45 One set is indicated by the lengths 6 and 7 and the other by the lengths 8 and 9. It will be observed that the lengths of each set are connected together as at 10, and also that one length, 6, of one set is connected 50 by a cross-over portion 11, to that length, 9, of the other set that is not coaxial therewith. In this way, lengths 6 and 9, which are connected together by cross-over portion 11, receive stresses that act in opposite directions 55 and therefore tend to neutralize each other by reason of said cross-over portion.

We claim:

A hinge including a wire bent into two sets of parallel lengths, said sets being arranged end to end, and the lengths of each set being connected together, one length of one set being connected by a cross-over portion to that length of the other set that is not coaxial therewith. 60 65

Signed at Brooklyn, in the county of Kings, and State of New York, this 30th day of July, 1921.

ARTHUR F. DERSE.
WILLIAM B. WILSHUSEN.
